United States Patent Office

Des. 219,259
Patented Nov. 24, 1970

219,259

NAILING MACHINE OR SIMILAR ARTICLE

Garry R. Perkins, West Chicago, Ill., assignor to Spot-nails, Inc., Long Island City, N.Y., a corporation of New York

Filed July 23, 1969, Ser. No. 18,354

Term of patent 14 years

Int. Cl. D8—02

U.S. Cl. D8—61

FIG. 1

Des. 219,259

PAGE 2

FIG. 2

FIG. 4

FIG. 3

FIG. 6

FIG. 5

FIG. 1 is a side elevational view of a nailing machine or similar article showing my new design.

FIG. 2 is an opposite side elevational view thereof.

FIG. 3 is a top plan view thereof.

FIG. 4 is a bottom plan view thereof.

FIG. 5 is a front elevational view thereof.

FIG. 6 is a rear elevational view thereof.

I claim:

The ornamental design for a nailing machine or similar article, as shown.
